UNITED STATES PATENT OFFICE.

OTIS A. MYGATT, OF NEW YORK, N. Y.

DESIGN FOR A REFLECTOR FOR ARTIFICIAL LIGHTS.

SPECIFICATION forming part of Design No. 36,215, dated February 3, 1903.

Application filed June 3, 1901. Serial No. 63,048. Term of patent 7 years.

To all whom it may concern:

Be it known that I, OTIS A. MYGATT, of New York, in the county of New York and State of New York, have invented a new, original, and ornamental Design for a Reflector for Artificial Lights, which is described in the following specification, reference being had to the accompanying drawings, in which—

Figure 1 is a side elevation of a reflector in which my design is embodied. Fig. 2 is a broken section of the same.

The body A of the reflector is of transparent glass approximating the form of a segment of a sphere and having a scalloped edge a. The outer surface of the spherical part of the shade is covered with four-sided pyramids C, with their bases close together, while the inner

surface of the reflector is smooth; but being of transparent material the ornamentation shows through. 20

Above the spherical part of the reflector there is a straight band D and above this a rounded ring or band B.

What I claim is—

The ornamental design for reflector for artificial lights, substantially as shown and described. 25

In testimony whereof I affix my signature in presence of two witnesses.

OTIS A. MYGATT.
